(57) **CLAIM**

The ornamental design for a motorcycle front light, as shown and described.

DESCRIPTION

FIG. 1 is a top, left, front perspective view of a motorcycle front light showing our new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

The uniform broken line showing in FIGS. 1-7 is for the purpose of illustrating portions of the motorcycle front light and forms no part of the claimed design.
